US00D819077S

(12) **United States Design Patent** (10) **Patent No.:** **US D819,077 S**
(45) **Date of Patent:** **** May 29, 2018**

(54) **DISPLAY SCREEN OR PORTION THEREOF WITH ICON**

(71) Applicant: **Apple Inc.**, Cupertino, CA (US)

(72) Inventors: **Aurelio Guzmán**, San Jose, CA (US);
Christopher Wilson, San Francisco, CA (US)

(73) Assignee: **Apple Inc.**, Cupertino, CA (US)

(**) Term: **15 Years**

(21) Appl. No.: **29/606,371**

(22) Filed: **Jun. 4, 2017**

(51) LOC (11) Cl. **14-04**

(52) U.S. Cl.

USPC **D14/489**

(57) **CLAIM**

The ornamental design for a display screen or portion thereof with icon, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with icon showing the claimed design;

FIG. 2 is a second embodiment thereof; and,

FIG. 3 is a third embodiment thereof.

The broken lines in the figures show a display screen or portion thereof, and form no part of the claimed design.
